UNITED STATES PATENT OFFICE.

JACQUES E. BERTIN, OF PARIS, FRANCE.

SEWING-MACHINE.

SPECIFICATION forming part of Letters Patent No. 225,553, dated March 16, 1880.

Application filed February 25, 1878. Patented in England, December 3, 1877.

To all whom it may concern:

Be it known that I, J. E. BERTIN, of Paris, France, have invented an Improved Sewing-Machine, of which the following is a specification.

This invention relates to an improvement in sewing-machines designed especially for sewing gloves; and it consists in the combination of parts, as hereinafter described, and particularly recited in the claim.

The drawings represent, in Figure 1, a side view; Fig. 2, a plan; Fig. 3, a sectional plan on line A B, Fig. 1; Fig. 4, a detached view.

O is the driving-shaft, to which power is applied in the usual manner. The cam C on said shaft imparts intermittent reciprocating movement to the rack e, and this, through the pinion a, imparts a rotary motion to the circular needle. (Shown in detached view, Fig. 4.) The cam C' imparts a reciprocating motion to the needle-arm d, the path of the needle being in a plane parallel with that of the circular needle. The cam C² imparts to the arm X a vibratory movement, the arm X carrying a hook which moves in a path substantially at right angles to the path of the two needles, and so that the two needles and hook operate together to form the stitch, in the usual manner for this class of machines.

A and B are two disks, arranged on vertical shafts o' and o² supported in bearings D D', and to the shafts an intermittent rotary movement is imparted by means of a wheel, L, on the driving-shaft, having but a single tooth, which, at each revolution, engages with one of the teeth of the wheel K on the shaft I and imparts to it a partial rotation, which is communicated to the shaft o' o² by bevel-pinions F H, shaft G, and gears F', E', and E.

The two disks A B run together in the same plane, and just below the stitch-forming mech-

anism. The work is passed between them and is fed by this intermittent rotary movement.

The bearing D is formed on one arm, q, of a lever hung below, the other arm extending to the opposite end of the machine, where it is forced down by a spring bearing vertically upon it, the tendency of which is to force the disk A toward the disk B, and so grip the work between the two, the spring yielding for variable thickness. At the spring end of the lever attachment is made with a pedal, so that the operator may raise that end of the lever to open the disks whenever he desires so to do.

The guide f is a finger extending over or near the point where the stitch is made, so as to govern that portion of the work vertically.

In connection with the guide f is a second finger, g, which lies close down upon the disk and against the work opposite where the needle enters, and so as to resist the thrust of the needle, and which tends to stretch or draw the leather out of shape.

I am aware that two feeding-disks have been used to present the work to the stitch-making mechanism of a sewing-machine, and therefore do not broadly claim such disk as of my invention.

I claim—

The combination of a stitch-making mechanism, the two feeding-disks A B, and the fingers f g, substantially as and for the purpose specified.

In testimony whereof I have signed my name to this specification before two subscribing witnesses.

J. E. BERTIN.
